FLOATING ROOF FOR STORAGE TANKS

William G. McCullam, Elizabeth, N. J., assignor to
Standard Oil Development Company, a corpora-
tion of Delaware

Application June 16, 1932, Serial No. 617,566

6 Claims. (Cl. 220—26)

This invention relates to improvements in roofs or decks for storage tanks, especially those used for volatile liquids such as low boiling petroleum oils (gasoline and the like). The invention is particularly adapted to the construction of floating roofs but some of the principles of design may be advantageously used in roofs which are secured in place.

A principal object of the invention is to provide a roof of light weight, self-buoyant material, for example, balsa wood or equivalent wood. The roof is made up of laminations and is suitably oil-water- and fire-proofed as described herein.

Another object of the invention is to improve the fastening means used to hold the seal on the floating roof.

Another object of the invention is to provide means for securing a floating roof in an elevated position when it is desired to inspect or clean the tank below the roof level.

Further objects and advantages of the invention will be apparent from the following description read in connection with the accompanying drawings, in which

Fig. 1 is a top plan view of a storage tank provided with a floating roof made according to this invention.

Fig. 2 is an enlarged vertical section on line 2—2 of Fig. 1.

Fig. 3 is a similar view indicating alternative methods of securing the laminations on the roof together.

Figs. 4, 5 and 6 are plan views showing a preferred way of laying out sections for the building up of the floating roof.

Fig. 7 is a view similar to Fig. 2 showing an alternative method of building up the laminated structure.

Fig. 8 is a vertical section through the edge of the roof showing the sealing ring and the means for securing the ring to the roof.

Fig. 9 is a vertical section on line 9—9 of Fig. 8.

Fig. 10 is a view similar to Fig. 8 but indicating the connection of the ring retaining means with a roller for guiding the up and down movement of the floating roof, and

Fig. 11 is a section through the roof and the tank indicating the means for sustaining the roof in an elevated position.

Referring first to Figs. 1 and 2, reference number 1 indicates the side wall of a storage tank, for example, a tank such as is used for storing gasoline. A floating roof 2 is placed in the tank with the usual clearance between the roof and the wall. This clearance is closed by the sealing

ring 14 hereinafter described. The roof has a manhead 3 of any suitable construction. In general the roof will be flat, but other shapes may be adopted.

In accordance with this invention the body of the roof is made up of laminations of material such as balsa wood, which is light weight, self-buoyant in gasoline, and easily treated so as to prevent absorption of gasoline. As shown in Fig. 2, three layers of balsa wood 4, 5 and 6, are provided, each layer being made of strips which are laid at an angle to the layer next beneath. The layers are secured together by oil-proof and water-proof marine glue or similar material. A supporting structure in the form of battens 7 of white pine or the like is provided. As shown in Fig. 1 these battens are arranged in the form of a grid beneath the laminations. Suitable cross joints are provided where the battens intersect. The battens are secured to the bottom layer of the roof by aluminum nails 8 or in any other suitable way.

In Fig. 3 additional means for securing the layers of balsa wood or the like together are illustrated. For example, aluminum nails 8a may be driven at an angle from one layer into the next adjacent, or hardwood dowel strips 9 may be inserted through the layers. The opening above the strip may be covered with plastic wood 10.

When large roofs are to be constructed it is necessary to build it up of sections of laminated wood. A desirable pattern for these sections is indicated respectively 11, 12 and 13 in Figs. 4, 5 and 6. For example, in a roof having a diameter of 59'2", it is desirable to provide 16 sections as in Figs. 4 and 8 each as in Figs. 5 and 6.

The entire roof is preferably painted with a phenol-formaldehyde coating or equivalent material so as to make the wood impervious to oil and water. Additional protection against absorption of liquids may be provided in the form of thin metal sheets 4a and 5a (Fig. 7) inserted between the laminations. It is desirable to fire-proof the roof by suitable means such as a thin metal cover 6a with joints crimped or welded.

The preferred type of sealing means between the tank wall and the roof as shown in Figs. 8, 9 and 10, is a ring 14 of leather, rubber, or other resilient material such as is commonly used in seals of this type. The means provided by the present invention are in the manner of securing the ring to the roof. For this purpose a clamp in general S-shaped designated 15 is provided. The bottom turn of the clamp has teeth 16 adapted to sink into the lower layer of the roof. The middle

turn of the clamp runs parallel with the top of the roof and is embedded in suitable packing material 17 such as the material known as transite. The inner ends 14a of ring 14 are brought together over the packing material. An aluminum plate 18 overlies the ends 14a. To secure the assembly together an aluminum wedge 19 is driven between the aluminum plate 18 and the upper portion of the S-shape clamp. This is recessed at 20 to receive the wedge.

In Fig. 10 a similar construction is shown but the S-shape clamp is modified so as to serve as a support for a roller 21. This roller is adapted to run on guides as is usual in the construction of floating roofs. In this figure, 22 indicates the clamping means and 23 the extension comprising a bearing 24 in which the shaft of the wheel turns. An aluminum wedge 25 is driven between the top of the roof and the bottom of extension 23 to hold the wheel in proper position. In Fig. 11 means are shown for supporting the roof at a convenient height so that men may work beneath it to clean out the tank. This means comprises V-shape supports 26 secured to the under surface of the roof. In the bottom of the tank are secured tressels 27 by means of bolts fastened to the bottom of the tank. In the ordinary operation the roof will be turned so that the V-shape supports do not make contact with the tressels. However, when it is desired to clean out the tank the roof is turned so that when it sinks with the withdrawal of the liquid, the V-shape supports will rest on tops of the tressels and hold the roof at a convenient height.

The present invention provides a satisfactory roof of low cost which can be installed in tanks even of the largest size. The sectional construction makes fabrication in the field easy. Although reference has been made to specific materials in the illustrative description given above, it will be understood that other woods, metals, and fabrics may be used.

Various changes and alternative arrangements may be made within the scope of the appended claims, in which it is my intention to claim all novelty inherent in the invention as broadly as the prior art permits.

I claim:

1. A floatable sectional tank roof structure comprising a plurality of sections adapted to be assembled edge to edge so as to form a unitary structure conforming to the contour of the tank walls, each section comprising a plurality of laminae, of which a predominant number are self buoyant, placed one above the other, in angular relationship to one another, means for securing one lamina to the other, means for sealing the laminae against moisture and absorption of material in the tank, and non-ferrous means for securing one section to another. 10

2. A floatable sectional tank roof structure according to claim 1 in which the self buoyant laminae are formed from thin sheets of balsa wood. 15

3. A floatable sectional tank roof structure according to claim 1 in which at least one laminae of each section comprises a thin sheet of non-ferrous metal placed between alternate laminae 20 of a self buoyant material.

4. A floatable sectional tank roof structure according to claim 1 in which the means for sealing the laminae against moisture and absorption of liquid in the tank comprises a coating of an oil and water impervious material on each lamina and a thin sheet of fire resistant material secured to the uppermost laminae after the sections have been assembled. 25

5. A floatable sectional tank roof structure according to claim 1 in which the non-ferrous means for securing one section to another comprises a plurality of wooden battens in the form of a grid in which the points of intersection of the respective battens is substantially equidistant from all sides of the laminated section immediately above, secured by holding means not including iron to the under surface of the roof. 30

6. A floating roof for storage tanks consisting of a plurality of thin sheets of a self-buoyant material disposed one above the other, thin sheets of non-absorbent, non-buoyant material disposed between the self-buoyant sheets, a fire-proof covering for the exterior of the roof and non-ferrous means for securing one sheet to another to form a unitary, laminated structure. 35 40 45
